UNITED STATES PATENT OFFICE.

FREDERIC L. THOMPSON, OF NEW BEDFORD, MASSACHUSETTS, ASSIGNOR
TO THE PAIRPOINT MANUFACTURING COMPANY, OF SAME PLACE.

DESIGN FOR A METALLIC PATTERN-STRIP.

SPECIFICATION forming part of Design No. 22,919, dated November 28, 1893.

Application filed October 20, 1893. Serial No. 488,736. Term of patent 7 years.

To all whom it may concern:

Be it known that I, FREDERIC L. THOMPSON, of New Bedford, in the county of Bristol and State of Massachusetts, have invented and produced a new and original Design for a Metallic Pattern-Strip, of which the following is a specification, reference being had to the accompanying drawings, in which—

Figure 1 is a plan view showing my new pattern strip and the design thereof, and Fig. 2 is a side view thereof.

The leading feature of my design consists in raised scroll and flower work arranged substantially in line and of the character illustrated.

A is a flower followed by the beaded scroll B the edges b b' of which are curved toward edge 1 of the pattern strip. Between edges b b' is bead work b^2 . The curved edge b terminates in leaf work at b^3 and in a bead at b^4 . The curved edge b' terminates in beads b^5 b^6 . Following the scroll B is a scroll D the tongues

d of which extend slantingly toward edge 2 of the pattern strip while tongue d' curves backwardly toward scroll B. A scroll F follows scroll D, its edge f being re-entrant at f' . This scroll terminates in a bead f^2 next which is a flower A' which is followed by a scroll G having a bead g . Scroll G is re-entrant at g' and terminates in an ornamental boss g^2 following which is a scroll H having tongues h curving toward edge 1 of the pattern strip. This arrangement of scroll and flower work may be repeated, if desired, in ornamenting various articles of manufacture with pattern strips containing my new design.

What I claim is—

The design herein shown and described for a metallic pattern strip.

FREDERIC L. THOMPSON.
